Primary Examiner — Ramzi S Almatrahi*(74) Attorney, Agent, or Firm* — Volpe and Koenig, P.C.**CLAIM**

The ornamental design for a monitoring camera, as shown and described.

DESCRIPTION

FIG. 1 is a perspective view of a monitoring camera in accordance with our design;

FIG. 2 is a right side elevational view thereof;

FIG. 3 is a left side elevational view thereof;

FIG. 4 is a top plan view thereof;

FIG. 5 is a bottom plan thereof;

FIG. 6 is a front elevational view thereof; and,

FIG. 7 is a rear elevational view thereof.

The broken lines depict portions of the monitoring camera in which the design is embodied that form no part of the claimed design. The dot-dash broken lines adjacent to the shaded areas represent the bounds of the claimed design.
